R. AND A. FEVOLA,

RADIATOR,

APPLICATION FILED SEPT. 25, 1920.

1,375,500.

Patented Apr. 19, 1921.

UNITED STATES PATENT OFFICE.

ROSE FEVOLA AND ANTONIO FEVOLA, OF BROOKLYN, NEW YORK.

RADIATOR.

1,375,500.

Specification of Letters Patent. Patented Apr. 19, 1921.

Application filed September 25, 1920. Serial No. 412,751.

To all whom it may concern:

Be it known that we, ROSE FEVOLA and ANTONIO FEVOLA, citizens of the United States, residing at Brooklyn, in the county 5 of Kings and State of New York, have invented new and useful Improvements in Radiators, of which the following is a specification.

This invention relates to improvements 10 in radiators and particularly to steam or hot water radiators provided with individual heating devices, and the principal object is to provide a device of this nature which shall be simple of construction, inexpensive to manufacture, and efficient for 15 the purpose for which it is designed.

Another object is to provide novel circulating devices.

Another object is to provide a novel 20 safety control for the device whereby the flow of fuel will be automatically governed by the heat maintained in the radiator.

With these and incidental objects in view, the invention consists in certain novel construction and combination and arrangement 25 of parts, the essential features of which are hereinafter described and claimed, and which are fully illustrated in the accompanying drawing comprising one sheet, in 30 which:—

Figure 1 is a vertical sectional, end-to-end view of our improved radiator.

Fig. 2 is a vertical sectional view taken substantially in line 2—2 of Fig. 1.

Fig. 3 is an enlarged vertical sectional view of the burner and adjacent parts.

Fig. 4 is an enlarged detail view of the coil and burner cover, showing the door for permitting cleaning and lighting.

Like characters of reference refer to like parts in all views.

Referring to the drawing in detail, 1 represents the sections or loops of the radiator which are secured together and which 45 are formed so as to provide top and bottom water-circulating passage ways 2 and 3 and connecting columns 4. Supported in any desired manner in the base of the radiator as upon a base plate 5 is a cylinder 6 of 50 perforated or foraminated material which cylinder incloses the water heating coil 7, said coil being connected at one end to a pipe 8 which conducts water from the passageway 3 to the coil, and at the other end 55 to a pipe 9 which conducts the heated water from the coil to the radiator sections.

A gas burner 10 is also supported from plate 5 and extends into the coil. Burner 10 is connected to the gas or fuel pipe 11 which is provided with a stop or regulat- 60 ing valve 12 and an automatically operable valve 13, the operation of which will be more fully described hereinafter.

A door 14 is provided in cylinder 6 to give access to the coil and burner for cleaning 65 the same.

The pipe 9 is provided with outlets into 70 passage ways 3 and 2 at 15 and 16 respectively, and at its upper end with a valve 17 and a funnel-shaped top element 18.

A steam drum or expansion tank 19 is secured to the top of the radiator and connects with passage 2 by two tubes 20 and 21. This tank is provided with a relief valve 22 and a steam gage 23, and also with an auto- 75 matic gas control which will be presently described.

A water gage is secured to the radiator and expansion tank at 24.

The automatic gas control comprises a 80 member 25 provided at its upper end with a rubber or other flexible diaphragm 26 carrying at its center a pin 27 that supports one end of a lever 28 pivoted at 29 on a fulcrum secured to member 25. A weight 30 is ad- 85 justable on the other arm of lever 28, and a stop 31 is secured to the drum 19 and limits the downward movement of the weighted arm. The longer arm of lever 28 is connected at its end by means of a chain 32 90 with the controlling lever 33 of the gas valve 13, said lever being normally held in its lowered open position by a spring 34 the lower end of which is connected to a bracket 35 secured to the gas pipe 11. 95

Where it is desired to have a direct connection to the water supply, the pipes may be connected in any suitable manner at 36.

In operation, the radiator may be filled at 18. The gas valve 12 is then opened and 100 the burner is lighted. As the water is heated, it flows from the coil into pipe 9 from which it is discharged at 15 and 16 into the radiator, circulating as indicated by the arrows, the cold water flowing out at the bottom through pipe 8 into the coil. Any steam generated will rise into the drum 19 through tube 20 and any condensed vapor is led back into the radiator through tube 21 from which it circulates again to the coil 110 7. As the steam pressure rises in drum 19, diaphragm 26 is flexed so as to raise pin 27

and thereby cause chain 32 to lift lever 33 to diminish the flow of gas, but stop 31 prevents the entire closing of the gas valve 13. The weight 30 may be adjusted along the lever 28 so as to regulate the amount of pressure necessary to cause closing of the valve. Should anything go wrong so that the gas would not be turned down, the relief valve 22 will permit escape of the surplus steam.

10 Any common type of damper regulator may be used to control the flow of gas.

A suitable air valve of common type is provided at 40. The radiator is adapted to withstand a pressure of twenty pounds per square inch but the relief valve operates at 15 not more than two.

While we have described what is deemed to be the most desirable embodiments of the invention, it is obvious that many of the details may be varied without in any way departing from the spirit of the invention; and we therefore do not limit ourselves to the exact details of construction herein set forth nor to anything less than the whole of the invention limited only by the appended claims.

What is claimed as new is:—

1. In a device of the class described, the combination of a plurality of radiator sections connected at their tops and bottoms for permitting free circulation, a water heating coil connected to said sections, a burner as-

sociated with said coil, a steam drum mounted on said radiator sections and communicating therewith, and automatic means connected with said drum and adapted to control the flow of fuel to said burner.

2. In a device of the class described, the combination of a plurality of radiator sections connected at their tops and bottoms for permitting free circulation, a water heating coil connected to said sections, a burner associated with said coil, a steam drum mounted on said radiator sections and communicating therewith, a connection to said steam drum, a flexible diaphragm secured to said connection, and a lever operable by said diaphragm to automatically control the flow of fuel to said burner.

3. In a device of the class described, the combination of a plurality of radiator sections having upper and lower intercommunications, a water heating coil connected to said sections, a burner associated with said coil, means for conducting fuel to said burner and including a valve, a steam drum mounted on and communicating with said sections, and means operable by pressure from said drum for controlling said valve.

In testimony whereof we have affixed our signatures.

ROSE FEVOLA.
ANTONIO FEVOLA.
